STEPLADDER

Alfred Pflugradt, Milwaukee, Wis.

Application April 29, 1933, Serial No. 668,525

6 Claims. (Cl. 228—21)

My invention relates to improvements in step-ladder assemblies.

The object of my invention is to provide a stepladder which is capable of being separated into relatively small units of such light weight as to be easily handled and adjusted for ordinary purposes, to facilitate reaching shelving, ceilings of rooms, or lower branches of trees. It is also my object to provide a jointed stepladder of great strength and durability, although constructed of separable parts.

It is my object to construct stepladders in units adapted to be used independently or in assembled superposed relation, one of the units being adapted to serve as the top of a stepladder of any height determinable by superposing such unit upon one or more associated units, each adapted to form the base of a stepladder or an intermediate section thereof.

Specific objects are to provide means for adequately and safely connecting stepladder units with each other; to provide adequate bracing for the connected units; to provide means whereby the units may be readily folded as a single package for storage and transportation purposes; and to provide safety locks for jointed stepladders, whereby they may be securely held in an extended relation.

In the drawings:

Figure 1 is a side elevation of a stepladder unit adapted to serve as the top unit for an extended ladder.

Figure 2 is a side elevation of an associate stepladder unit adapted to be used separately or in association with the unit shown in Figure 1, or with other units like that shown in Figure 2, and with which the unit shown in Figure 1 has been assembled as a top unit.

Figure 3 is an enlarged fragmentary view of one of the hinge joint connections of two assembled ladder sections.

Figure 4 is a view of the same showing said members and their connections in detached relation.

Figure 5 is an enlarged sectional view drawn to line 5—5 of Figure 2.

Figure 6 is a side elevation, showing two of the stepladder units in assembled relation to produce a stepladder of substantially double height as compared with that shown in Figure 1.

Figure 7 is a front elevation showing a modification.

Figure 8 is a side view, showing two of the units folded and prepared for storage.

Like parts are identified by the same reference characters throughout the several views.

The unit disclosed in Figure 1 is a short ladder having side bars 10 connected at intervals by cross bolts 11 and steps 12, the latter being preferably located directly above the bolts and supported by angle brackets 13, through the vertical flange of which the bolts preferably extend, as best illustrated in Figure 2. The horizontal flange of each bracket may serve as a spacer 65 interposed between the end of the step and the bolt, whereby the bolt is made to cooperate with the bracket in supporting the step from the associated side bar independently of screws or other connections, such as are ordinarily used to connect step supporting brackets with the side bars. 70

The top step or cap piece 15 is supported from the side bars 10 by special brackets 16, each connected with one of the side bars 10 by a bolt 17 which also serves to connect the associated brace bar 18 with the bar 10. The upper end of the brace bar 18 preferably has a metal sheath 75 19. 19.

In conformity with ordinary practice, the brace bars 18 are reenforced by diagonal cross braces 22 and are detachably connected with the side bars 10 by stays 23 having hook-shaped extremities adapted to removably engage projections 24 on the bars 10, whereby these stays 80 may be disconnected and folded upon the brace bars 18. The shelf 25 is also of ordinary construction and pivotally supported from the brace bars 10 by the shelf supporting arms 26. 85

It will be observed that the brace bars of each set are more widely spaced from each other than the step supporting side bars and so hinged thereto as to permit the brace bars to fold at the sides of the step supporting bars. For example, the brace bars 18 are so connected with the side bars 10 underneath the cap step 15 as to permit the brace bars to swing to a folded position at the sides and parallel with the bars 10, whereby the hinged extension bars 10a, hereinafter described, may be folded upon the edges of the bars 10 as shown in Fig. 8, and embraced by the extension bars 18b to form a compact package for transportation or storage. 90

The lower ends of the side bars 10 are provided with hinge members 31 having bearing faces 32 to receive a counterpart hinge member, as best shown in Figures 3 and 4. The hinge member 31 has a sheath-like extension 33 in which the lower end of the associated bar 10 is socketed. The hinge member 31 is apertured at 34 to receive a hinge pin 35, and at 36 to receive 105 110

a locking pin 37. The lower ends of the brace members are provided with sheaths 38 adapted to slide thereon and to be secured to the brace bars in either of two positions by a locking 5 detent 39.

Referring to Figure 2, it will be observed that 10 side bars 10a, connected by cross rods 11a, are employed to support a series of steps 12a, as above described with reference to the ladder 15 unit shown in Figure 1. This unit has no cap step, but the side bars 10a are provided with a hinge member 41 having a bearing face 42 and a sheath-like extension 43 in which the upper end of the associated ladder bar 10a is socketed. 20 The locking pin 37 is preferably connected with the step 12a by a suitable chain 45.

The side bars 18a of the brace are connected with a hinge member 41 by bolts 48 when the 25 unit is separately used as a small ladder. The cross braces 22a and stays 23a are similar to the corresponding parts 22 and 23 in Figure 1.

Assuming that the two ladder units illustrated 30 in Figure 1 and Figure 2 are to be assembled as shown in Figure 6, the brace bars 18 will first be disconnected by removing the bolts 48 and disengaging the stays 23a. Thereupon the side bars 10a of this unit may have the hinge members 41 at their upper ends connected by the hinge pins or bolts 35 (Figures 3 and 4) with the hinge 35 members 31 of the ladder unit illustrated in Figure 1. The hinge bolts or pintles 35 preferably have threaded inner ends to receive a special nut 50 provided with a pivoted handle 51 and an annular flange 52, whereby this nut may 40 be manually adjusted upon the pintle 35 to hold the bearing surfaces 32 and 42 in frictional contact with each other. It will be observed that the hinge member 41 has a shoulder at 53 upon which the lower margin 54 of the hinge member 31 may bear when the side bars 10 and 10a of the two ladder units are aligned.

When in the position of alignment the locking 45 pin 37 will be inserted in the holes 36a and 36 of the hinge members 41 and 31, thereby locking the hinge with the ladder sections 10a and 10 in alignment.

When the bolts 48 are removed to disconnect 50 the brace bars 18a from the hinge members 41 preparatory to assembly as a part of an extension ladder, these bolts 48 and their associated washers 56 are preferably inserted through apertures 57 in the sheath 43, whereupon they operate with the upper cross rod 11 for securely holding the sheath to its associated side bar 10a.

The brace bars 18a are then aligned with the 55 brace bars 18 of the Figure 1 unit, and the sheath 38 is moved downwardly to embrace the upper ends of the brace bars 18a and secured to both bars by the locking detents 39 of ordinary type.

The stays 23a may remain folded against the 60 side bars 18a when the parts are assembled to form the extension ladder shown in Figure 6. If desired, the lower ends of the bars 18a may be provided with sheaths 38a, similar to the sheaths 38, and similarly connected and adapted for adjustment to connect another extension unit in the same manner that the sheaths 38 are employed to connect the Figure 2 unit with the Figure 1 unit.

Also, the lower ends of the bars 10a of the 70 Figure 2 unit may be provided with hinge members 31a for connection with the step supporting side bars of a third unit. The sheaths 38a may be provided with ears 61 to which stay rods 62 are attached. These rods 62 may nor-

mally be folded along the brace bars 18a when not in use, but when the units are assembled to form an extension ladder the hook-shaped upper ends 63 of these stay rods may be engaged with projections 64 on the hinge members 31a. Also, these stay rods may be provided with pivoted extension members 66, which also have hook-shaped ends 67.

The step supporting side bars 10b and brace 80 bars 18b of the lower unit may be outwardly or divergently curved in the direction of their lower extremities, as shown in Figure 7, and in that event this unit will always be used as the lower unit, regardless of the number to be assembled. Therefore, the side bars of this unit will not 85 require hinge members at their lower ends.

Referring to Figure 8, it will be observed that 90 when the units are connected in superposed relation as shown in Figure 7, the lower set of bracing bars may be disconnected and the lower set of step supporting bars may be swung upon the intermediate hinge to folded position after first withdrawing the key 37. Thereupon the detached brace bars may be placed upon the folded sections and secured thereto by links 68 similar to the stay 23 and normally disposed in parallel 95 relation to the brace bars.

I claim:

1. A set of stepladders provided with mutually 100 engageable coupling members adapted to connect the stepladder elements in superposed relation to form a single stepladder of increased height, one of said stepladders having a capping top step, and the other stepladder having its steps spaced equally from each other and from 105 the lower step of the other ladder when secured in extended relation thereto.

2. A stepladder provided with hinge members 110 having a capping top step and secured to the upper ends of its side bars, and also having hinge members secured to the lower ends of its side bars, in combination with an associated stepladder having hinge members at the upper ends of its side bars engageable in hinged relation to the hinge members at the lower ends of the side 115 bars of the first mentioned ladder, each of said ladders being provided with bracing members adapted to be coupled end to end when the step supporting portions are superposed, the bracing members of one ladder being provided with sliding couplings, each adapted in one position for connecting bracing members of both ladders of the set when the pairs of bracing members are 120 in end to end adjustment.

3. The combination with a set of stepladders 125 having step supporting side bars and a pair of bracing members normally pivotally connected with the upper ends of the respective side bars, means for connecting the side bars end to end, and means for manually releasing one pair of 130 bracing bars from their associated side bars and connecting them end to end with the bracing bars of the other stepladder, the bracing bars of one ladder being provided with sheaths adapted to slide thereon to a joint covering position 135 of engagement with the bracing bars of both ladders of the set when the pairs of bracing bars are in end to end adjustment.

4. A stepladder unit having step supporting 140 side bars provided with one-way hinge members at their lower ends adapted to be coupled to extension side bar members, in combination with bracing bars pivotally connected with the upper ends of said side bars and provided with sheaths at their lower ends adapted to be moved 145 150

downwardly into a joint covering relation to extension braces.

5. A set of step ladders having step supporting and bracing bars adapted to be pivotally connected with each other or coupled end to end with corresponding ladder members of another set, the step supporting side bars of each step-ladder having hinge member sheaths at their respective ends, one set of sheaths being adapted 10 to allow its associated brace bars to fold upon the sides of the step bars and the other set of sheaths being adapted to allow the extension

step bars to fold upon the inner margins of those of the other set.

6. A set of folding step ladders, each having hinged bracing members, one of said ladders having a capping top step, and the other having its top step below the hinge connection of its bracing member, and means for separately securing the last mentioned step and bracing members to the lower ends of the respective step and bracing members of the ladder having the capping top step. 80 85
